UNITED STATES PATENT OFFICE.

JOSEPH MORENILLA, OF CHICAGO, ILLINOIS.

HAIR-WAVING DEVICE.

Application filed January 25, 1923. Serial No. 614,863.

To all whom it may concern:

Be it known that I, JOSEPH MORENILLA, a subject of the King of Spain, and a resident of Chicago, in the county of Cook and State of Illinois, have invented a new and Improved Hair-Waving Device, of which the following is a full, clear, and exact description.

This invention relates to improvements in hair dressing implements, and has particular reference to a device for producing a Marcel wave.

An object of the invention is to provide an improved means for waving a strand of hair in two directions by the cooperation of members, all of which are controlled from a single source.

Another object is to provide improved means for securing a strand of hair in position between two cooperating members in such manner that said strand may be effectively waved in two directions.

The above and other objects will appear more clearly from the following detail description, when taken in connection with the accompanying drawings, which illustrate a preferred embodiment of the inventive idea.

In the drawings—

Figure 1 is a side elevation of the device showing the parts in their normal positions;

Figure 2 is a similar view of the parts in the position assumed at the termination of the initial stage of operation;

Figure 3 is a longitudinal sectional view of the device showing the parts in completely operated position;

Figure 4 is a plan view of the device with the parts in the position shown in Figure 3;

Figure 5 is a transverse section on the line 5-5 of Figure 3;

Figure 6 is a detail perspective view of a spring employed in connection with the invention; and

Figure 7 is a plan view of a strand of hair showing the same waved in accordance with the present invention.

The device is shown as comprising a base member 10, the inner portion of which is bifurcated to provide opposed plates 11, the free extremities 12 of which are bent into overlapping relation and secured to the end of a handle 13 by means of a screw or other fastener 14. Mounted between the plates 11 is a clamping member 15, which is partially supported by means of a pin 16 extending between the plates 11 of the member 10 and

operable in curved slots 17 formed in opposite sides of the inner end of the member 15. This inner end of the member 15 is provided with an arcuate slot 18, the outer end of which receives a pivot 19 carried by the intermediate portion of an iron 20, the inner end of which is pivoted at 21 to a handle 22 which cooperates with the handle 13. When the parts are in normal position, as shown in Figure 1, the pivot 19 also extends through the outer ends of arcuate slots 23 formed in the side plates 11 of the member 10 and the slots 18 and 23 are so disposed that when the parts are moved to the position shown in Figure 2, the same will register with each other. The pivot 19 is yieldingly maintained in the outer extremities of the slots 18 and 23 by a resilient member 24 which is bent upon itself, as shown in Figure 6, the intermediate portion of said member being secured to the handle 13 by means of the screw 14 and the extremities of said member being engaged with the pivot 19 to normally exert an outward pressure thereagainst. The handle 22 has a bent plate 25 secured thereto, said plate including an extension 26 in which the pivot 21 is mounted and also including the curved arms 27 which extend exteriorly on both sides of the plates 11. The outer extremities of the arms 27 are connected by a pivot 28 which normally engages in the outer ends of arcuate slots 29 formed in the plates 11.

By reason of this construction, it will be seen that when the handles 13 and 22 are initially compressed or moved toward each other the member 10 will swing about the pivot 19 and although said member will have a tendency to move outwardly in swinging about said pivot, by reason of the slots 23, the same will be prevented from doing so by the resiliency of the spring 24. In thus moving about the pivot 19 the pin 16 will be caused to move to the opposite ends of the short slots 17 formed in the member 15 and at the same time the pivot 28 will move longitudinally of the slots 29 toward the inner ends thereof. This relative movement of the members 10 and 15 continues about the pivot 19 until the pivot 28 reaches the inner ends of the slots 29, at which time the slots 18 and 23 will be in registration, or substantially so.

When the parts have reached the position shown in Figure 2, further movement of the handles 13 and 22 toward each other will be

about the pivot 28 inasmuch as the same has now reached the inner ends of the slots 29 and the slots 18 and 23 are in registration. It will be obvious that movement of the handles toward each other subsequent to the parts reaching the position shown in Figure 2 and with the pivot 28 in the position shown in said figure, the spring 24 will be unable to further yieldingly maintain the pivot 19 in the outer extremities of the slots 18 and 23. This pivot 19 being carried by the iron 20, the inner end of which is pivotally connected at 21 to the handle 22, it will be apparent that as the latter handle is moved toward the position shown in Figure 3, an inward pull upon the iron 20 will be effected and the pivot 19 will move inwardly in the slots 18 and 23 against the tension of the spring 24 to the position shown in Figure 3, where the parts are illustrated as being completely operated. The configuration of the spring 24 is such that when the handles 13 and 22 are released said spring will react to restore the parts to their normal positions.

The outer portion of the base member 10 is preferably of trough-like formation in cross section, as best illustrated in Figure 5, the central portion of said member 10 being curved longitudinally to provide a recess for receiving a part of the strand of hair and the longitudinal edges of said member 10 being bent upon themselves to provide flanges 30 which are spaced from the side walls of the central portion. Also along each longitudinal edge of the central portion of the member 10 the same is provided with a plurality of openings 31 for receiving the projections or teeth 32 of the clamping member 15 when said member is in the position shown in Figure 3. The clamping member 15 at its outer end is enlarged, as clearly shown in Figure 4, and provided with an elongated opening 33 upon the longitudinal edges of which said projections or teeth 32 are formed. As the base and clamping members 10 and 15 and the iron 20 are brought into cooperating relation the strand of hair is engaged between the iron and the bottom of the central portion of the member 10 so that said strand will be waved longitudinally. Simultaneously with the action the teeth or projections 32 extend into the openings 31 and secure the portion of the strand engaged by the clamping member in such position that said portion will be prevented from any longitudinal movement relative to the base and clamping members. However, in the final movement of the handles from the position shown in Figure 2 to that illustrated in Figure 3, the longitudinal movement of the iron 20 with respect to the base and clamping members previously described is utilized to wave that portion of the strand engaged between the base member and iron

in a transverse direction so that when the strand is removed from the device it will have the appearance shown in Figure 7. To facilitate the production of the transverse wave the member 20 is provided with a plurality of teeth 34, the effective surfaces of which are pitched inwardly and gradually increase in thickness toward the portion of the iron adjacent the bottom of the central portion of the base member 10.

What is claimed is:

1. In a hair waving device, a base member having a troughlike portion, a clamping member cooperating with said base member, a pair of handles operable to move said members into cooperating relation, and an iron also actuated by said handles and movable longitudinally with respect to said members and within the confines of the troughlike portion of said base member when said members are operated.

2. In a hair waving device, a base member having a troughlike portion, a clamping member cooperating with said base, a pair of handles operable to move said members into cooperating relation, and an iron actuated to initially move with one of said members when the same are operated and subsequently moved longitudinally of said member and within the confines of the troughlike portion of said base member.

3. In a hair waving device, a base member, a clamping member cooperating therewith, a yieldingly supported pivot about which said members are initially movable, and a second pivot about which said members are subsequently movable as the same are brought into cooperating relation.

4. In a hair waving device, a base member, a clamping member cooperating therewith, an iron associated with said members, a pivot carried by said iron about which said members initially move as the same are being brought into cooperating relation, and a second pivot about which said members subsequently move to adjust said iron longitudinally of said members.

5. In a hair waving device, a base member, a clamping member cooperating therewith, an iron associated with said members, a pivot carried by said iron about which said members initially move as the same are being brought into cooperating relation, a second pivot about which said members subsequently move, and means for moving said iron longitudinally with respect to said members during the subsequent movement thereof.

6. In a hair waving device, a base member, a clamping member cooperating therewith, an iron associated with said members, a yieldingly supported pivot carried by said iron and about which said members initially move as the same are being brought into cooperating relation, and a second pivot about

which said members move before reaching their cooperating positions.

7. In a hair waving device, a pair of co-operating handles, a base member carried by one of said handles, a clamping member associated with said base member, pivots about which said base and clamping members are movable toward each other, one of said members having an initial movement about one of said pivots when said handles are actuated, and a subsequent movement in the same direction about another pivot when said handles are further actuated.

8. In a hair waving device, a pair of co-operating handles, a base member carried by one of said handles, a clamping member associated with said base member, pivots about which said base and clamping members are movable toward each other, one of said members having an initial movement about one of said pivots when said handles are actuated, and a subsequent movement in the same direction about another pivot when said handles are further actuated, an iron cooperating with said base and clamping members and movable with one of them by the initial actuation of said handles, and movable relative to said members upon the further actuation of said handles.

9. In a hair waving device, a pair of co-operating handles, a base member carried by one of said handles, a clamping member associated with said base member, pivots about which said base and clamping members are movable toward each other, one of said members having an initial movement about one of said pivots when said handles are actuated, and a subsequent movement in the same direction about another pivot when said handles are further actuated, and an iron cooperating with said base and clamping members and movable with one of them by the initial actuation of said handles, and movable longitudinally with respect to said members during the further actuation of said handles.

10. In a hair waving device, a pair of co-operating handles, an iron connected to one of said handles, a base member having a pivotal connection with said iron and about 50 which connection said base member is movable when said handles are initially actuated, a second pivotal connection for said base member about which said member is moved upon further actuation of said handles, and 55 a clamping member cooperating with said base member to clamp a strand of hair therebetween when said handles are actuated.

11. In a hair waving device, a base member having a central trough-like portion for receiving a strand of hair and also having a plurality of openings contiguous to the edges of said portion, a clamping member cooperating with said base member and having projections engageable in the openings 65 therein to secure said strand in position between said members, and an iron associated with said members and operable in one direction to impart a longitudinal wave to said strand and in another direction to impart a 70 transverse wave to the portion of said strand in the trough-like portion of said base member.

12. In a hair waving device, a base member having a trough-like portion, a clamping 75 member cooperating with said base member to secure a strand of hair in said trough-like portion, and an iron movable into said trough-like portion and longitudinally with respect thereto, said iron having teeth each 80 having a surface of varying thickness engageable with hairs of said strand when the iron is moved longitudinally, whereby said strand is waved transversely.

13. In a hair waving device, a base member, a clamping member cooperating therewith, an iron associated with said clamping member and having pivotal and longitudinal movements with respect to said base member, and a spring against the tension of which 90 said iron is longitudinally movable.

JOSEPH MORENILLA.
